FIG. 4

Des. 202,839

PAGE 3

FIG. 5

FIG. 7

FIGURE 1 is a side elevational view of an aircraft, showing our new design;

FIGURE 2 is a front elevational thereof;

FIGURE 3 is a fragmentary side elevation of the tail showing the horizontal stabilizers in a horizontal position;

FIGURE 4 is a top plan view of the aircraft;

FIGURE 5 is a top perspective view thereof;

FIGURE 6 is a top fragmentary perspective view of the aircraft illustrating the wing leading-edge flap in a lowered position; and

FIGURE 7 is a bottom fragmentary perspective view of the aircraft showing the wing leading-edge flap in a lowered position.

The dominant features of our design reside in those portions shown in full lines.

The invention described herein may be manufactured and used by or for the Government of the United States

of America for governmental purposes without the payment of any royalties thereon or therefor.

We claim:

The ornamental design for an aircraft, substantially as shown and described.
